UNITED STATES PATENT OFFICE.

HENRY FRANKLIN FARLEY, OF KALONA, IOWA, ASSIGNOR OF ONE-HALF
TO WILLIAM KELLEY, OF SAME PLACE.

ROTARY ENGINE.

SPECIFICATION forming part of Letters Patent No. 678,652, dated July 16, 1901.

Application filed January 29, 1901. Serial No. 45,254. (No model.)

To all whom it may concern:

Be it known that I, HENRY FRANKLIN FARLEY, a citizen of the United States, and a resident of Kalona, in the county of Washington 5 and State of Iowa, have invented a new and Improved Rotary Engine, of which the following is a full, clear, and exact description.

The object of the invention is to provide a new and improved rotary engine which is 10 simple and durable in construction, very effective in operation, and arranged to permit of convenient reversing and of utilizing the motive agent to the fullest advantage.

The invention consists of novel features 15 and parts and combinations of the same, as will be fully described hereinafter and then pointed out in the claims.

A practical embodiment of the invention is represented in the accompanying drawings, 20 forming a part of this specification, in which similar characters of reference indicate corresponding parts in all the views.

Figure 1 is an end elevation of the improvement. Fig. 2 is a transverse sectional side 25 elevation of the same. Fig. 3 is a sectional side elevation of the same on the line 3 3 in Fig. 1. Fig. 4 is a sectional plan view of the same on the line 4 4 in Fig. 1. Fig. 5 is a perspective view of one of the abutments, and 30 Fig. 6 is a face view of the exhaust-valve.

The cylinder A is mounted on a suitably-constructed base B, and in the cylinder-heads is journaled the main driving-shaft C, carrying a piston D concentric with the cylinder 35 and provided with piston-heads E E', located diametrically opposite each other and mounted to slide in recesses formed in the piston D, springs E² pressing the said piston-heads outwardly to hold their outer ends in contact 40 with the inner surface of the cylinder A. On opposite sides of the piston D are arranged abutments F F', of which only one is active at a time, each abutment when in use forming a supply-chest of the motive agent for the 45 cylinder, as hereinafter more fully described. The abutments F F' are made hollow for this purpose and are fulcrumed on supply-pipes G G', extending to the outside of the cylinder and connected with a main supply-pipe 50 G², leading to a boiler or other suitable source of motive-agent supply. The ends of the

pipes G G' within the cylinder are perforated, as shown in Fig. 4, so that the motive agent can pass from the pipes into the hollow abutments F F'. The forward ends of the abutments F F' are formed with openings F², through which passes the motive agent into the cylinder to rotate the piston D. 55

When the abutment F is in use, as shown in Fig. 2, then the motive agent passing into the cylinder acts successively on the heads E E' to turn the piston D in the direction of the arrow a'. When it is desired to reverse the engine, the abutment F is moved outward into a recess A', formed in the cylinder A, 65 while the other abutment F' is moved from its recess A² into the cylinder, so as to become the active abutment, and then the motive agent passing from this abutment F' into the cylinder acts on the piston-heads E E' to rotate the piston D in the inverse direction of the arrow a'. The under sides of the abutments F F' are curved, as is plainly indicated 70 in Fig. 2, so that when the piston-head E or E' comes in contact with the said under side then the corresponding piston-head is pushed 75 inward against the tension of its spring E² to pass the abutment, and as soon as this takes place the spring E² again forces the corresponding abutment outward to take steam. 80

The abutments F F' are simultaneously moved by mechanism under the control of the operator—that is, when one abutment moves into an active position the other moves out of an active position. For the purpose described the abutments are provided with stems H H', extending through the walls of the recesses A' A² to the outside of the cylinder, and the outer ends of the said stems H H' are connected by links I I' with a lever 90 J, fulcrumed on the driving-shaft C and provided with a hand locking device J', adapted to engage a notched segment J², secured on the cylinder-head. When the operator unlocks the lever J and swings the same from 95 the left to the right to the position shown in Fig. 3, then the abutment F is moved into an active position, while the abutment F' is moved into an inactive position—that is, outward into the recess A². When the lever J is swung from the right to the left, then the abutment F' is swung inward into an active 100

position, while the abutment F is swung outward into its recess A' to become inactive.

In order to control the amount of motive agent passing from the abutments F F' into the cylinder at the time an abutment is in an inactive position, I provide slide-valves K K' over the openings F² of the abutments, and said slide-valves are provided with stems K² K³, each of which carries at its outer end an adjustable collar K⁴, connected by a link L with a lever L', fulcrumed on a bracket N, attached to the corresponding stem H or H' of the abutments F or F'. Each of the levers L' is connected by a link L² with a hand-lever O, having a locking device O', adapted to engage a segment P, pivotally connected with said bracket N, and with a link P', fulcrumed on the cylinder A, as is plainly shown in Figs. 1 and 2. The lever O is fulcrumed on the segment P, and the latter moves with the corresponding bracket N when the abutments F F' are shifted by the operator manipulating the lever J, as above described.

By the operator operating the hand-lever O a swinging motion is given to the lever L', which by the link L and collar K⁴ imparts a sliding motion to the corresponding valve K or K', so as to shift the same relatively to the opening F² to allow more or less motive agent to pass into the cylinder A, according to the direction in which the hand-lever O is shifted.

The exhaust in front of a piston-head takes place through an exhaust-port a, formed in a circular valve R, (see Figs. 3 and 6,) extending between the front face of the piston D and the cylinder-head A³ and mounted to turn loosely on the shaft C. The port a registers with a segmental exhaust-channel Q, formed on the inner side of the cylinder-head A³ and leading to an exhaust-pipe Q', as is plainly indicated in Figs. 1 and 3. The exhaust-valve R is connected with a hand-lever S, fulcrumed on one of the cylinder-heads by means of a pin S', extending through a segmental slot S², formed in said head A³ of the cylinder. The lever S is provided with a locking device S³ for locking the lever on a segment S⁴ and holding the valve R in the desired position—that is, with its port a either at the right or the left portion of the exhaust-channel Q. When the abutment F is in use, the valve R closes the left-hand half of the exhaust-channel Q, and when the abutment F' is in active position then the operator has to shift the valve R to bring the port a to the right-hand half portion of the channel Q.

A packing and an adjusting disk T is arranged between the cylinder-head A⁴ and the rear face of the piston D, and set-screws T', screwing in said head, serve to adjust the disk transversely to hold the piston in proper contact with the exhaust-valve and prevent leakage of steam.

Having thus fully described my invention, I claim as new and desire to secure by Letters Patent—

1. A rotary engine, comprising a cylinder, a piston mounted to turn therein and having a yielding piston-head, and a valved abutment in the cylinder and having a cam-surface for pressing the piston-head, the abutment being hollow, connected with the motive-agent supply, and arranged to open into the cylinder, as set forth. 75

2. A rotary engine, comprising a cylinder, a piston mounted to turn therein and having a yielding piston-head, an abutment in the cylinder and having a cam-surface for pressing the piston-head, the abutment being hollow, connected with the motive-agent supply, and arranged to open into the cylinder, and a valve controlling the opening of the abutment leading to the cylinder, as set forth. 80

3. A rotary engine, comprising a cylinder, a piston mounted to turn therein and having a yielding piston-head, an abutment in the cylinder and having a cam-surface for pressing the piston-head, the abutment being hollow, connected with the motive-agent supply, 85 and arranged to open into the cylinder, a valve controlling the opening of the abutment leading to the cylinder, and means for manually adjusting said valve, to control the motive agent from the abutment to the cylinder, 90 as set forth.

4. A rotary engine, comprising a cylinder, a piston mounted therein and having a plurality of yielding piston-heads, a plurality of abutments mounted to swing and each having a cam-surface for pressing the piston-heads, each abutment being hollow, connected with the motive-agent supply and opening into the cylinder, and a valve controlling the outlet of each abutment, as set forth. 100 105

5. A rotary engine, comprising a cylinder, a piston mounted therein and having a plurality of yielding piston-heads, a plurality of abutments mounted to swing and each having a cam-surface for pressing the piston-heads, each abutment being hollow, connected with the motive-agent supply and opening into the cylinder, valves for controlling the outlets of the abutments, and supply-pipes for the said abutment and forming fulcrums 110 115 for the abutments, as set forth.

6. A rotary engine, comprising a cylinder, a piston mounted therein and having a plurality of yielding piston-heads, a plurality of abutments mounted to swing and each having a cam-surface for pressing the piston-heads, each abutment being hollow, forming a supply-chest connected with the motive-agent supply and opening into the cylinder, and means under the control of the operator 120 125 for simultaneously moving the abutments, to bring one into an active position while the other moves into an inactive position, as set forth.

7. A rotary engine, comprising a cylinder, a piston mounted therein and having a plurality of yielding piston-heads, a plurality of abutments mounted to swing and each having a cam-surface for pressing the piston- 130 135

heads, each abutment being hollow, connected with the motive-agent supply and opening into the cylinder, and a valve under the control of the engineer for controlling the exhaust, the said exhaust-valve being mounted to turn and provided with an exhaust-port registering with a segmental groove in a cylinder-head, and an exhaust-pipe connected with the said cylinder-head groove, substantially as shown and described.

8. In a rotary engine, the combination with a cylinder having recesses in opposite sides, and a piston mounted in the cylinder and provided with yielding piston-heads, of hollow swinging abutments mounted in the recesses and connected with the motive-agent supply, each abutment being provided with an outlet in its free end, and with a stem leading out through the wall of its recess, an operating-lever, and links connecting the lever with the stems of the abutments, as set forth.

9. In a rotary engine, the combination with a cylinder having recesses in opposite sides, and a piston mounted in the cylinder and provided with yielding piston-heads, of hollow swinging abutments mounted in the recesses and connected with the motive-agent supply, each abutment being provided with an outlet in its free end, means for simultaneously moving the abutments one into active position while the other moves into inactive position, a slide-valve for the outlet of each abutment, and means for operating the said valve, as set forth.

10. In a rotary engine, the combination with a cylinder, and a piston mounted in the cylinder and having yielding piston-heads, of hollow swinging abutments mounted at opposite sides of the cylinder, each abutment be-

ing connected with the motive-agent supply 40 opening into the cylinder, and provided with a projecting stem, means connected with the stems of the abutments for operating them, a slide-valve for controlling the opening of the abutment leading into the cylinder, and 45 a lever mechanism for operating the said valve, as set forth.

11. In a rotary engine, the combination with a cylinder, a piston mounted in the cylinder and having yielding piston-heads and 50 swinging abutments each provided with an outlet and with a projecting stem, of a slide-valve for controlling the outlet of the abutment, a lever pivotally mounted on the stem of each abutment, a link connecting one end 55 of the lever with the stem of the slide-valve, an operating-lever, and a link connecting the operating-lever with the first-named lever, as set forth.

12. In a rotary engine, the combination 60 with a cylinder having a recess in each side, and a piston mounted in the cylinder and provided with yielding piston-heads, of a perforated motive-agent-supply pipe in each recess, a hollow abutment mounted on each perforated pipe, and provided with an outlet at 65 its free end, and means for simultaneously operating the said abutments to move one into active position and the other into inactive position, as set forth.

In testimony whereof I have signed my name to this specification in the presence of two subscribing witnesses.
